GARMENT HANGER

James H. Terral, Hooks, Tex.

Application October 11, 1954, Serial No. 32,636

Term of patent 14 years

(Cl. D80—8)

Fig. 1

Fig. 3

Fig. 2

I claim:

The ornamental design for a garment hanger, as shown.
